WASHING AND CLEANING MACHINE
 George Kuhn, Silver Spring, Md., assignor to
 General Motors Corporation, Dayton, Ohio, a
 corporation of Delaware

Original application October 17, 1936, Serial No.
 106,080, now Patent No. 2,282,332, dated May 12,
 1942. Divided and this application May 11,
 1942, Serial No. 442,641

2 Claims. (Cl. 68—27)

1

This invention relates to the washing and cleaning of fabrics and articles and more particularly to power driven washing and cleaning machines.

This application is a division of my copending application Serial No. 106,080, filed October 17, 1936, for Washing and cleaning machine, now Patent No. 2,282,332, granted May 12, 1942.

This application discloses improvements in, and variations of, the washing machine disclosed in my prior filed application, Serial No. 92,500, filed July 25, 1936 now Patent No. 2,142,961 granted Jan. 3, 1939.

This invention is directed to the prevention of tangling of the articles being washed.

The invention in its several aspects will be understood from the following description considered in connection with the accompanying drawings forming a part thereof, and in which:

Fig. 1 is a partial vertical sectional view, illustrating one manner in which the interior of the tub may be divided into a plurality of compartments;

Fig. 2 is a horizontal sectional view taken on line 2—2 of Fig. 1;

Like characters of reference refer to the same or similar parts throughout the several views.

Referring to the drawings, reference character 10 designates the tub of the machine which is preferably cylindrical in form with a closed bottom 11 and an opening 12 at the top which may be closed by a hinged cover 13. The tub 10 is secured to a supporting pedestal 14 which also serves to support the operating mechanism for the washing element.

The washing element is rapidly reciprocated with relatively short strokes in the treating fluid contained in the tub, and includes one or more scrubbing surfaces which also produce circulatory motion of the washing fluid and pulsations in the fluid which are sufficiently vigorous to flex and agitate flexible articles being treated and to cause the fluid to be forced through the fabric of the articles as more fully described in my said copending applications. In this instance, the discs are constructed and arranged so as to cause the treating fluid and the articles being treated, to circulate in general as indicated by the flow lines in Fig. 1, that is, toward the center of the tub at the lower end of the washing ele-

2

ment, upwardly at the center and along the element through the scrubbing zone, which may be considered as the space immediately surrounding the washing element, then radially outwardly from the upper end or portion of the element and downwardly at the wall or the peripheral portions of the tub. Although the washing element may be constructed of rigid materials such as metal, hard rubber, Bakelite, etc., I prefer using elastic and flexible material such as live rubber, or suitable rubber composition reinforced with fabric, metal or other material where necessary. Greater circulation of the fluid and more gentle treatment of the articles is thus obtained. More specifically, the discs 16 and 17 of the washing element may be flexible rubber cups. These cups are disposed so as to be concave upwardly, as shown in Fig. 1, and as they are reciprocated, the bottom of the cups flex and the walls, particularly the upper edge portions, expand and contract producing a pumping action which sucks the fluid and the articles at the bottom of the tub radially inwardly toward the washing element and into the scrubbing zone. Disc 18 should also be flexible but it should not possess the degree of concavity of cups 16 and 17. Instead it should have an upwardly inclined flange on the order of that shown, so arranged that it functions to take hold of the articles brought into the scrubbing zone by the cups 16 and 17 and to feed them upwardly in a series of relatively fast jerks toward the disc or discs above. Disc 19 should be semi-flexible, that is, more rigid than the lower discs and is constructed and arranged to slap or pound the articles moving upwardly in the scrubbing zone and to push them and the treating fluid radially outwardly toward the wall of the tub in the upper portion of the fluid. This disc is curved outwardly and upwardly as shown, with a concave lower surface, and in the form of the machine shown, is positioned to operate below the surface of the body of washing fluid. During operation, disc 19 functions to project fluid and the articles therein, outwardly toward the wall of the tub. Upon reaching or nearing the wall of the tub, the fluid and the articles will be forced to flow downwardly toward the bottom of the tub due to the action of the bottom discs 16 and 17 as previously described.

The discs on the washing element should be spaced apart a distance sufficient to allow each disc to fully perform its intended function. Although two pumping discs 16 and 17 are shown, a single disc of this character may be used where less vigorous circulation is desired.

The carrying and operating mechanism for the washing element illustrated includes a vertically disposed shaft 28 arranged and supported to be rapidly reciprocated and upon which the discs 10 16 to 18 are mounted in any suitable manner, such as disclosed in my copending application, now Patent No. 2,282,332.

A member designated 23 which is partly submerged in the fluid when the washing element is in normal or intermediate position as indicated in Fig. 1, and is constructed and disposed so that during movement of the washing element it will not strike or slap the surface of the fluid. Specifically, this non-splashing means in the form shown, is described and claimed in another application, Serial No. 442,639 filed May 11, 1942.

Where large quantities of certain articles of clothing such as those having long strings, belts, straps, etc., having a natural tendency to tangle, are being washed, it may be desirable to employ means to reduce or prevent tangling thereof. One such means is illustrated and consists of a plurality of partitions 70, 71 and 72 which divide the washing or treating compartment of the tub 10 into a plurality of separate compartments 73, 74 and 75. These partitions are secured at their outer and lower edges to the tub 10 and extend radially inwardly to points just short of the washing element so as not to interfere with its operation. The inner edges of the partitions preferably should be spaced from the washing element and its discs a distance sufficient to prevent any possibility of pinching or catching the clothes or articles between the partitions and the washing element or any of its discs. With this arrangement it will be perceived that there is no possibility of the clothes or articles in one compartment becoming tangled with clothes or articles in any of the other compartments. Also with this arrangement it is possible to wash articles of different character at the same time in the same washing machine without mixing of the articles. Obviously, the number of compartments into which the tub is divided for this purpose may be two or more and the form and shape of the partitions may be such as to secure the results desired. For example, the partitions may extend from the wall of the tub radially inwardly any suitable distance short of the washing element, such as half way for instance, which will be sufficient to overcome the tendency of the clothes to tangle. Although the inner edges of the partitions illustrated are straight and vertically disposed, these inner edges may have inclined or curved configurations. The aforesaid edge surfaces should connect with the opposite side portions of the partitions by smooth curved surfaces to avoid sharp edges which might catch the articles being treated or cause undue wear. The partitions shown are imperforate, but perforated partitions may be utilized, including screens and the like. It will be understood that the use of partitions in the tub to divide the washing compartment into a plurality of separate compartments is of general application to washing and fluid treating machines and is not limited in its use to machines employing the form of washing element herein disclosed.

Forms of washing elements other than dis-

closed may be employed, if desired, including washing elements with but a single disc. However, it should be understood that the invention is not limited to the particular forms of washing elements herein disclosed, but that other forms and arrangements may be employed without departing from the principles of the invention.

Although the washing elements disclosed herein are centrally or axially disposed in the tub, it will be understood that other positions of the washing element in the tub will produce satisfactory results. The washing element may be placed at any suitable off-center position and may even be disposed closely adjacent the wall of the tub, if desired. Additionally, the washing element may be actuated from the top of the tub rather than from the bottom as illustrated.

Inasmuch as the rate and direction of circulation of the fluid, the intensity of the washing action, and other factors depend upon the shape, size, number and relative position and inclination of the surfaces of the discs as well as upon the operating speed of the washing element, it will be readily perceived that any or all of these factors may be modified as desired to meet any particular requirements.

Due to the unique character of the circulatory motion obtained in the machine of my invention the shape of the tub is immaterial and rounded corners or inclined walls or the like are unnecessary, because during operation, the clothes or other articles discharged upwardly and outwardly upon the surface of the fluid impose their weight upon the other articles disposed at the outer peripheral portions of the tub and force these other articles downwardly and into the sphere of influence of the lower disc or discs of the washing element.

It will be understood that the direction of fluid circulation obtained during operation of the washing elements may be reversed merely by inverting the surfaces of the discs of the washing elements.

It will be obvious that changes may be made in the form, location, relative arrangement and the materials of the several parts of the machine disclosed without departing from the principles of the invention. Accordingly no intention is entertained to limit the invention except by the scope of the appended claims.

What is claimed is as follows:

1. Apparatus of the character described comprising a tub to receive liquid and articles to be washed, an agitator mounted in the central portion of said tub for vertical reciprocatory movement, said agitator having means responsive to the vertical reciprocatory movement of the agitator through the liquid to produce a unidirectional toroid of said liquid and articles to be washed, means to reciprocate said agitator vertically to produce said toroid, and a substantially vertical radial baffle extending from the side wall of said tub into proximity to said agitator a sufficient distance to sever said toroid and reduce intertangling of said articles to be washed.

2. Apparatus of the character described comprising a tub to receive liquid and articles to be washed, an agitator mounted in the central portion of said tub for vertical reciprocatory movement, said agitator having means responsive to the vertical reciprocatory movement of the agitator through the liquid to produce a unidirectional toroid of said liquid and articles to be washed, means to reciprocate said agitator vertically to produce said toroid, and a plurality of

circumferentially spaced substantially vertical radial baffles extending from the side wall of said tub into proximity to said agitator a sufficient distance to sever said toroid into segments and prevent intertangling of articles to be washed between said segments.

GEORGE KUHN.
